5 Claims. (Cl. 202—115)

This invention relates to coke ovens and more particularly to an oven for distilling or coking coal in thin layers.

In the production of coke, the individual pieces of which have varying sizes, in one and the same oven, it has already been suggested to charge the coal into molds having the desired size and to stamp the coal therein as far as required. According to these known methods the material charged in the molds remains stationary in the distillation chamber during the process of distillation. The distillation chamber is heated step by step to the temperature of distillation in the manner well known in the coke oven art. The molds are bottomless, being mere frames lacking a bottom and the coal rests directly upon the bottom of the distillation chamber. At the top the mold is covered by a perforated cover.

It has now been found that the coke ovens known in the prior art can be greatly improved by charging the material to be distilled also into bottomless molds which are, however, arranged for displacement in the oven. During the shifting of these molds the coal to be distilled passes through the different temperature zones, while resting upon the heating bottom in direct contact with it.

It has further been suggested to move the material to be distilled along the distillation apparatus. However, in those cases the material has always been charged into molds having bottom plates, which involves the great disadvantage of a poor heat economy. Moreover an automatic discharge of coke from the individual molds is not possible where these cells maintain their original position. It has also been suggested to move the bottom, which carries the material. This latter design, however, results in considerable difficulties in the construction and operation of the oven. In particular, this arrangement requires special packings, such as floating cups or the like. Moreover, of course, the movable parts of such apparatus are exposed to very considerable wear.

The present invention, while resulting in an optimum heat economy, permits of the use of a stationary construction of the entire oven without any movable packings. By moving the individual bottomless molds along a circular path or in a closed rectangular path the charging and discharging of the molds is carried out in continuous operation and the mold frames always remain in the indirectly heated chamber channels. The mold frames are so guided that simul-

taneously with one frame all or at least a plurality of frames are shifted.

Instead of a cover seated on each mold frame, stationary cover plates may be provided preferably, however, only at those places, where a covering of the material is found to be advantageous. These cover plates are held against movement together with the molds, but are arranged for vertical movement. The cover plates are designed to counteract too large an expansion of the coke when the inflating pressure during distillation becomes excessive; furthermore, the cover plates have the purpose of preventing too high and premature a heat reception of the material from above in the zone sensitive to temperature. Therefore, at these respective places the cover plates are insulated against heat radiation.

According to the present invention several systems are arranged one above the other. Such optional number of similar oven chambers arranged above each other permit of the simultaneous operation of the same as well as of charging and discharging by means of a common charging and discharging device at one and the same point of the oven. Preferably also the heating flues of the several stages are connected with each other in a manner such that the waste heat may be utilized most economically in the heating of the various stages.

Preferably the fine coal, before being charged into molds and being coked, is first subjected to a thermic treatment by heating the same up to about 100 to 250° C., as in this manner more valuable products are obtained.

In the drawings affixed to this specification and forming part thereof several embodiments of my invention are illustrated diagrammatically by way of example.

In the drawings:

Fig. 1 is a vertical cross section through a coke oven according to the invention showing at the left hand side of the figure the drive mechanism for all mold frames, while on the right hand side of the figure the charging and discharging device as well as the discharge of the distillation gases are shown.

Figs. 2, 3, 4 and 5 are horizontal sections through the embodiment of the invention according to Fig. 1 and along lines II—II, III—III, IV—IV, IVa—IVa and V—V of Figs. 6, 7, 8 and 9, respectively, and more particularly

Fig. 2 is a partial section through the oven chamber and through the mold frames arranged in a circle,

Fig. 3 is a similar section through the oven chamber, however, above the mold frames.

Fig. 4 is a partial section through the heating channels, while Fig. 4a is a similar section through 5 modified heating channels.

Fig. 5 is a similar section through the waste heat channels.

Figs. 6 to 9 illustrate two different modifications of the heating arrangement, and more 10 particularly

Fig. 6 is a vertical cross section along lines P₁—Q₁ in Fig. 3, while

Fig. 7 is a similar section taken along lines P₂—Q₂ in Fig. 3.

15 Fig. 3 is a section along lines N₁—O₁ in Fig. 4, while

Fig. 9 is a section along lines N₂—O₂ in Fig. 4a.

Fig. 10 is an elevation of part of another 20 embodiment of the invention, showing the twin chamber space, while

Fig. 11 is a similar elevation on a different plane, showing the heating channels.

Figs. 12 and 13 are vertical cross sections 25 taken along lines G—H of Figs. 10 and 11, respectively.

Fig. 14 is a vertical section taken along lines A—B in Fig. 10, while

Fig. 15 is a similar section taken along lines C—D in Fig. 10 and

30 Fig. 16 is a diagrammatic elevation of the oven block.

Referring now to the drawings and first to the embodiment of the invention shown in Figs. 1—9 the coal stored at *a* is charged to the distributor space *b*, wherefrom it is supplied through conveyor worms *c* into the charge boxes *d* and therefrom is passed into the mold frames *e*. As is best shown in Fig. 2 the sector-shaped mold frames *e*, which in the first embodiment of the invention 35 are arranged, by means of a toothed rim *h*, in a circle, are formed by radial ribs having corresponding outer boundaries. The mold frames *e* rest upon a stationary circular plate forming the heating surface. The charging and discharging 40 of each individual movable frame is effected by the stationary charging or discharging device. The coke discharged from the sector-shaped frames drops from all stages into a common cell discharge *f*, passing therefrom into the conveyor device *f*. While thus being conveyed, the coke can be cooled in any desired manner. The movement of the mold frames filled with material 45 to be distilled is carried out in a manner such that several pinions *g* mounted on a common driving shaft mesh with the outer toothed rim *h*. In order to further guide the mold frames also at several points of the inner running path guide 50 rollers *i* are arranged.

The heating is effected through the heating 55 bottom *k* preferably in such a manner that first the lowermost oven chamber is heated and the waste gases supplied to the chamber above it, adding thereto heating gases of higher temperature to obtain identical temperatures throughout 60 the stages. An amount of circulating heating gases corresponding to the amount of fresh heating gases supplied is discharged from the apparatus in order to prevent too great an accumulation 65 of heating gases. The heat energy of the heating gases discharged from the top and intermediate stages can, of course, be utilized in any desired manner. The gases required for the heating are supplied through gas pipes *l* to the 70 heating flues *m*, as shown more particularly in 75 Fig. 3, where the heating gases flow through the flues in descending direction, while according to Fig. 9 the heating gases rise in the flues. In either case the air enters the flues in Fig. 8 from the other side, however in Fig. 9 alternately 5 with the gas. In the lower heating system the first combustion of the main amount of the gas supplied from the furnace below the oven takes place in the combustion chamber *n*, the waste heat rising in zig-zag through the individual 10 heating flues *m* and being discharged into the waste heat channel *o*. In this manner the heating flues *m* are always supplied with small amounts of additional heat designed to replace the consumed amounts of heat and to safeguard 15 a uniform bottom temperature for all the heating flues. A part of the heat from these bottom heating flues *m* can be passed through adjustable channels *p* to the cover heating through flues *q* (Figs. 4 and 6—9); here adjustable 20 amounts of air can be introduced at the points *p* for control purposes (Figs. 3 and 8).

Except at the points of charge and discharge, cover plates *s* (Figs. 6—9) resting on or above the radial ribs prevent excessive inflation of the material to be distilled. These plates are so arranged, that they do not jeopardize the free mobility of the mold frames. For this purpose they are supported in a manner such that they are movable upwardly, but fixed in the direction of rotation. The plates are arranged in juxtaposition with their perforated or undulated outer edges abutting against each other and thus enabling the gases of distillation to pass into the waste flues. These cover plates are heated by the radiated heat from the flues *q* above them, and thus serve as top heating elements.

By insulating these plates, an excessive influence of the top heat can be avoided. This is 40 of particular importance insofar as in the first period of distillation an excessive heating of the top layer of the material to be distilled must be avoided in order to prevent the formation of foam. Therefore, at this stage of the process 45 of dry distillation of the coal heating must be chiefly effected solely from the bottom, so that the gases of distillation developed in the bottom layer can readily escape.

In adaption to the prevailing working conditions and quite particularly to the condition of the coal, the coke oven according to the present invention can be operated either at a uniform 50 or at a varying speed during one revolution.

The gases of distillation may be discharged 55 from each stage separately and, if desired, even within each stage at different points thereof. A further simple modification of this arrangement, as shown in the drawings, provides for the discharge of the gases of distillation at *t* (Fig. 9) 60 from a shaft rising through to all stages, in which the guide rollers *i* are supported for ready access.

A further embodiment of the invention is illustrated in Figs. 10 to 16. According to this embodiment of the invention, the mold frames, instead of being moved along a circular part, are circulated on two parallel tracks.

Referring now to Figs. 10 to 16, the mold frames 65 of all oven chambers are moved once during 70 the period of distillation through the chambers 75 and 31 in a manner such that by the simultaneous advancing of the frame at the end of each chamber the frames at the other end are forced to share in the movement. The material 76

to be distilled is circulated through distillation chambers arranged in parallel to each other. The frames at either end are shifted sideways from the track 30 onto the adjacent parallel track 31 and vice versa (Fig. 16).

All mold frames are open at the top and at the bottom. The coal charged into the frames is spread in thin layers on hollow heating elements 2 being uniform closed hollow bodies which form the bottoms and the top covers of the oven chambers.

In all oven chambers these bottoms or covers are interrupted at the places 3 where coal is filled in, and at the places 4 where coke is discharged, the charging and discharging being effected in all stages continuously from the top towards the bottom and from or to a central station.

The ground dry coal is arranged above each oven in a charging bunker 5 which communicates with the coal supply shaft passing through all the stages and which is closed in each stage by frames 6, which are open at the top and at the bottom for the passage of the coal and the lower ends of which are somewhat spaced from the top edges of the mold frames 1. The mold frames 6 extend to the oven bottom. Into these frames extend stirring devices 7 (Figs. 10 and 14), which move continuously within the coal charges during each longitudinal displacement of the mold frames 1, thus promoting the sliding and the complete charging of the frames, and which simultaneously are adapted to compress the charges. Each frame 6 is surrounded at the bottom by an angular frame 8, which is spaced somewhat from the same and rests with its bottom surface on the top edges of the mold frames. These angular frames 8 prevent the coal from leaving the mold frames 1 and level the mold in the same at a level limited by the top edges. Provision is made for emptying the coal shaft by closing a slide valve at the upper charging station and opening a bottom closure, whenever this should be desired, for example, for the purpose of removing emptied guide frames from the oven chambers or for other purposes.

The charging and discharging of the mold frames 1 takes place during their longitudinal displacement. The discharge is effected by means of plates 9 (Fig. 15), which are periodically moved upwardly and downwardly, in a manner such that the plates with the shoulders provided at their bottoms repeatedly strike the coke at short intervals. The plain top surfaces of these plates 9 serve as sliding surfaces for the dropping coke pieces. The discharge is promoted by a rocking motion of the plates 9. From all the oven chambers the coke is discharged into a common collector shaft 10, which at the bottom opens into a cell drum 11, which discharges the coke without permitting air to enter the oven chamber. The longitudinal and transversal displacements of the mold frames 1 are carried out intermittently, however, for all oven chambers simultaneously (or successively), by means of pushers extending through the oven wall. Presses 12 arranged outside the oven block are provided for actuating these pushers (Fig. 16).

The gases of distillation are discharged from the gas collector spaces 13 and 14 (Figs. 10-13) at either end of the oven block and are passed therefrom to a place where they are further treated. Cover plates 15 which are prevented from following the movement of the mold frames

are provided solely in those zones of the oven, in which it is required to counteract the pressure of inflation and to protect the coal against a premature excessive action of the heat of radiation from the top.

The heat energy required for the bottom heating is produced sideways of the oven block in a number of combustion places 16 (Figs. 10 and 14). The heating gases discharged from the heating elements 2 of one oven chamber are passed through connections 19 into the heating elements of an upper oven chamber, after the drop in temperature has been compensated by the supply of fresh heating gases having a higher temperature. The additional heat energy required is generated in additional combustion places of brickwork 17, and is distributed to the heating elements of the next following oven chamber to be heated up together with the waste heat from the lower oven chamber. In this manner a uniform heating of all oven chambers is effected, whereby a far reaching utilization of the waste heat is obtained. The excess gases are discharged through particular waste heat flues 18 (Figs. 10, 11) provided for each individual stage. The waste heat from the upper stage and from the waste heat flues 18 is passed through a collector channel 20 (Fig. 14) to a heat exchange device 21, where it is utilized in the preheating of the air. The air enters in an adjustable manner the heat exchanger 21 and leaves the device in counter current to the waste through the flue 23. The gases cooled in the heat exchanger are then supplied through the conduit 24 to the combustion places 16 at 16a in order to be mixed with the heating gases.

I wish it to be understood that I do not desire to be limited to the exact details of construction shown and described for obvious modifications will occur to a person skilled in the art.

I claim:

1. A coking oven comprising in combination, a stationary oven chamber, a stationary heating bottom in said chamber, shallow bottomless mold frames adapted to accommodate thin layers of coal and arranged for displacement on said heating bottom and in direct contact therewith, means for moving said mold frames through the oven while maintaining contact between said stationary heating bottom and the open bottom sides of the mold frames, and means for heating the coal in said frames to different temperatures in different parts of said chamber.

2. A coking oven comprising in combination, a stationary oven chamber, a stationary heating bottom in said chamber, shallow bottomless mold frames adapted to accommodate thin layers of coal and arranged for displacement on said heating bottom and in direct contact therewith, charging and discharging stations in said oven, and means for moving said mold frames to and from said stations, means for maintaining the open bottom sides of said mold frames, when moving, in contact with said stationary heating bottom, and means for heating the coal in said frames to different temperatures in different parts of said chamber.

3. A coking oven comprising in combination, a stationary oven chamber, a stationary heating bottom in said chamber, shallow bottomless mold frames adapted to accommodate thin layers of coal and arranged for displacement on said heating bottom and in direct contact therewith, charging and discharging stations in said oven,

and means for moving said mold frames in a closed path to and from said stations, means for maintaining the open bottom sides of said mold frames, when moving, in contact with said stationary heating bottom, and means for heating the coal in said frames to different temperatures in different parts of said chamber.

4. A coking oven comprising in combination, a plurality of superposed chambers, stationary heating bottoms in said chambers, shallow bottomless mold frames adapted to accommodate thin layers of coal and arranged for displacement on the heating bottoms of said chambers and in direct contact therewith, means for moving said mold frames through the oven while maintaining contact between said stationary heating bottom and the open bottom sides of the mold frames, means for heating the coal in said frames to different temperatures in different parts of each chamber, charging and discharging stations

10
15
20

in said oven, means connecting all said oven chambers with said charging and discharging stations, and heating flues for each chamber arranged for communication with each other.

5. A coking oven comprising in combination, a stationary oven chamber, a stationary heating bottom in said chamber, shallow bottomless mold frames adapted to accommodate thin layers of coal and arranged for displacement on said heating bottom and in direct contact therewith, means for moving said mold frames through the oven while maintaining contact between said stationary heating bottom and the open bottom sides of the mold frames, means for heating the coal in said frames to different temperatures in different parts of said chamber, and means associated with said oven for preheating the coal to about from 100° to 250° C.

OTTO HELLMANN. 20
